RECORDING AND REPRODUCTION OF
ELECTRICAL IMPULSESGlenn Leslie Dimmick, Westmont, N. J., assignor
to Radio Corporation of America, a corpora-
tion of Delaware

Application June 8, 1933, Serial No. 674,805

6 Claims. (Cl. 179—100.3)

This invention relates to the photographic recording and reproduction of electrical impulses, such as those of audio frequency, and has for its principal object the provision of an improved

5 apparatus and method of operation whereby the reproduced impulse distortion which tends to result from the imperfect resolving power of the photographic record is minimized or avoided.

As pointed out in a copending application, 10 Serial No. 610,302, filed May 9, 1932 and assigned to the same assignee as the present application, the limited resolving power of the photographic film available for recording audio or other impulses causes the valleys of the high frequency 15 waves to be filled in or fogged, thus partially rectifying the higher frequency components of the recorded impulses. Also the high frequency peaks are likely to be underexposed and soft. The effect on the reproduced impulses is the introduction of a second harmonic distortion and 20 a distortion which results from a change in the average transmission and follows the envelope of the higher frequencies. In accordance with this invention, both these types of distortion are 25 avoided or minimized by the provision of two similar records displaced in phase by 180 degrees and arranged to be simultaneously reproduced and combined for operating a sound reproducer or loud speaker.

30 The fogging of the valleys of the high frequencies in a film recording results in the following types of distortion. Due to the loss of transmission in the valleys the amplitude of the light modulation is decreased and an attenuation of 35 the high frequencies results. The change in the shape of the wave would result in the introduction of both even and odd harmonics. The reduction of the average transmission when high frequencies are recorded results in extraneous 40 sounds, the frequencies of which depend upon the envelope of the high frequencies recorded. The latter distortion is by far the most serious since it produces disagreeable extraneous sounds accompanying the sibilants. The method of recording and reproducing outlined, however, eliminates this "zero shift" distortion resulting from 45 the change in the average transmission and at the same time completely eliminates all even harmonic distortion. Odd harmonics and attenuation of the high frequencies are still present. The first odd harmonic, the third, is not of such great importance because the filling in of the valleys of the recorded waves does not usually 50 become appreciable for frequencies below half 55 of the frequency range recorded. For instance,

in a studio recording channel a 9,000 cycle wave is attenuated to less than half its value at low frequencies, whereas the attenuation of a 4,500 cycle wave is quite small.

It will be apparent that the "zero shift" distortion and second harmonic distortion, is eliminated by the push-pull recording and reproducing system if it is considered that the resulting electrical wave would be symmetrical about the "time" axis. It is obvious that the total transmission at the instant W—W shown on Figure 2 is the same as the transmission at instant V—V which is displaced a half length along the time axis. The electrical wave will therefore have the same numerical value at W—W and at V—V, but will have opposite signs. It can be proven mathematically that a wave which is symmetrical about the time axis is free from even harmonic distortion and that the average value of the wave does not vary with its amplitude.

The invention will be better understood from the following description when considered in connection with the accompanying drawings, and its scope will be pointed out in the appended claims.

Referring to the drawings:

Fig. 1 is a diagrammatic illustration of a recording system to which the invention has been applied.

Fig. 2 illustrates the type of record produced 30 by the system of Fig. 1.

Fig. 3 is a diagrammatic showing of a system adapted to reproduce the record of Fig. 2.

Fig. 4 illustrates a modified form of recording system which facilitates the elimination of ground 35 or background noise.

Fig. 5 illustrates a light mask control element which forms a part of the system of Fig. 4, and

Fig. 6 illustrates the type of record which is 40 produced by the system of Fig. 4 and is adapted to be reproduced by the system of Fig. 3.

The recording system of Fig. 1 includes a source 10 from which a rectangularly-shaped light beam is applied through a lens 11, a mask 12 and a lens 13 to a galvanometer mirror 14 45 which is vibrated in accordance with the impulses to be recorded. From the mirror 14, the light beam is reflected through a lens 15, a light slit member 16 and lenses 17 and 18 to a photographic or light sensitive record which is moved lengthwise by means of a drum 20 and the cooperating rollers 21 and 22.

It will be observed that the light beam is biased to a position where it illuminates a rectangularly-shaped area midway between the ends of the light 55

slit in the member 16. When this beam is vibrated longitudinally of the light slit, the two records A and B of Fig. 2 are produced. These records are 180 degrees out of phase with one another and, when reproduced together, rectify the distortional effects previously mentioned.

The records A and B are reproduced by the apparatus of Fig. 3. This apparatus includes a source 23 from which light is projected through an optical system 24, the records A and B on the film 19, a lens 25 and lenses 26 and 27 to a push-pull type of photo-electric or other light sensitive device 28. The device 28 includes an anode 29 which is connected through a battery 30 to an intermediate terminal of a transformer winding 31 and with cathodes 32 and 33 which are connected respectively to the opposite end terminals of the winding 31. Inductively associated with the winding 31 is a secondary winding 34 which is connected through suitable amplifying apparatus to a sound reproducer in a manner well known to those skilled in the art.

Since the records A and B are not only identical but are 180 degrees out of phase, it necessarily follows that their simultaneous reproduction results in the cancellation of the distortional effects previously resulting from fogging of the high frequency valleys and softening of the high frequency peaks.

30 The transparent section between the records A and B is of constant width and of course leaves something to be desired where ground noise due to film grain, scratches, dust etc. is an important consideration. The recording system of Fig. 4 is designed to eliminate such ground or background noise.

40 This apparatus differs from that of Fig. 1 in that the rectangularly-apertured mask 12 is replaced by a triangularly-apertured mask 35 which is arranged to be moved by an electric motor device 36 energized in accordance with the envelope of the impulses to be recorded in any suitable manner such as that disclosed by United States Patent No. 1,855,197.

45 As indicated more clearly in Fig. 5, the rectified or envelope current referred to in the aforementioned patent is supplied through a pair of terminals to the coils 38 to 41 which are so wound on the pole pieces of a magnet 42 as to cause the triangular light beam to move transversely across the light slit as indicated by the arrow C. This beam is also moved longitudinally of the light slit by the mirror 14 which is vibrated in accordance with the impulses to be recorded. Under these 50 conditions, the records E and F (see Fig. 6) are not evenly spaced from one another but the distance between them varies with the amplitude of the impulses, this result being effected by the movable mask 35 which moves the triangular light beam 55 further across the light slit when the amplitude is high and vice versa. At all times, however, the spacing between the records E and F is kept at the minimum permitting satisfactory reproduction, thus maintaining a low ratio of ground to 60 signal noise. The records E and F may of

course be reproduced by the apparatus of Fig. 3.

Having thus described my invention, what I claim is:

1. An impulse recording system including a light source, means provided with a triangular aperture for defining the shape of the beam of light from said source, a member provided with a narrow slit, means for imaging the said aperture on the said slit, means for vibrating the said beam in accordance with impulses to be recorded and means for moving the said aperture in accordance with the envelope of said impulses. 5

2. An impulse recording system including a light source, means provided with a triangular aperture for defining the shape of the beam of light from said source, a member provided with a narrow slit, means for forming an image of said slit on a film, means for imaging the said aperture on the said slit, means for vibrating the said beam in accordance with impulses to be recorded and means for moving the said aperture in accordance with the envelope of said impulses. 15

3. An impulse recording system including a light source, means provided with an aperture of varying dimensions for defining the shape of the beam of light from said source, a member provided with a narrow slit, means for imaging the said aperture on the said slit, means for vibrating the said beam in accordance with impulses to be recorded and means for moving the said aperture in accordance with the envelope of said impulses. 25

4. An impulse recording system including a light source, means provided with a triangular aperture for defining the shape of the beam of light from said source, a member provided with a narrow slit, means for imaging the said aperture on the said slit, means for vibrating the said beam longitudinally of the said slit in accordance with impulses to be recorded and means for moving the said aperture in accordance with the envelope of said impulses. 30

5. An impulse recording system including a light source, means provided with a triangular aperture for defining the shape of the beam of light from said source, a member provided with a narrow slit, means for imaging the said aperture on the said slit, means for vibrating the said beam longitudinally of said slit in accordance with impulses to be recorded and means for moving the said aperture transversely of the slit in accordance with the envelope of said impulses. 45

6. An impulse recording system including a light source, means provided with a triangular aperture for defining the shape of the beam of light from said source, a member provided with a narrow slit, means for forming an image of said slit on a film, means for imaging the said aperture on the said slit, means for vibrating the said beam longitudinally of said slit in accordance with impulses to be recorded and means for moving the said aperture transversely of the slit in accordance with the envelope of said impulses. 50
